UNITED STATES PATENT OFFICE.

JOSEPH KAUFMAN, OF NEW YORK, N. Y.

RAZOR-BLADE HOLDER.

No. 921,998.

Specification of Letters Patent.

Patented May 18, 1909.

Application filed December 28, 1908. Serial No. 469,554.

To all whom it may concern:

Be it known that I, JOSEPH KAUFMAN, a citizen of the United States, residing at New York, in the county of New York and State of New York, have invented certain new and useful Improvements in Razor-Blade Holders; and I do hereby declare the following to be a full, clear, and exact description of the invention, such as will enable others skilled 10 in the art to which it appertains to make and use the same.

This invention relates to improvements in handles for razors, and more particularly to holders adapted especially for detachably 15 sustaining safety razor blades during the operation of stropping.

The object in view is the provision of a razor blade handle or support which is foldable and extensible for purposes of compactness in the first instance, and for increasing the length of the grip in the latter, means being provided for preventing accidental folding of the parts during the stropping operation.

With this and further objects in view, as will hereinafter in part be set forth and in part become obvious, the invention comprises certain novel constructions, combinations and arrangements of parts as will be 30 specified and claimed.

In the accompanying drawings,—Figure 1 is a perspective view of a holder embodying the features of the present invention. Fig. 2 is a view in side elevation thereof. Fig. 3 is an edge or plan view thereof. Fig. 4 is a view in side elevation thereof with the parts shown in their folded condition. Fig. 5 is a horizontal section of a fragment of the parts seen in Fig. 2, the section being taken on the plane indicated by line 5, 5 of said figure, and the parts being shown on an enlarged scale. Fig. 6 is a transverse section taken on the plane indicated by line 6, 6 of Fig. 1. Fig. 7 is a view similar to Fig. 5 showing a slightly 45 modified form of construction.

Referring to the drawing by numerals, 1 indicates a casing having its free edges formed into gripping jaws 2, 2, between which the blade is adapted to be slid for being clasped and retained as indicated in Fig. 1. The casing 1 is enlarged inwardly from the jaws sufficiently for receiving the usual stiffening or back plate of the blade, as clearly seen in Fig. 6. The casing 1 terminates at one end in a pair of flat parallel plates 3 which are spaced apart, and a pref-

erably, relatively flat, comparatively thin handle 4 has one of its ends pivotally mounted between the plates 3, the parts being held in the stated position by a rivet 5 passed through the plates 3 and the end of the handle 4, and preferably formed with relatively heavy heads 6, designed to prevent bodily separation of the plates 3 under the strain of the spring action hereinafter mentioned. The free end of each plate 3 is provided with an inwardly turned lug or laterally extending detent 7, which may be stamped from the material of the plate, the said detents being adapted in operation to extend into an aperture 8 formed through the handle 4, so as to hold said handle rigidly against folding toward the casing 1.

Obviously, the detents 7 may be of any desired size, and in closing or opening the handle, said detents will, of course, spring outwardly and slide along the faces of the handle 4 until they arrive at the opening 8, or at the edge of the handle, the laterally sprung condition being indicated in dots in Fig. 3, and the springing action occurring between the free end of each of the plates 3 and the point of engagement of the rivet 5.

In operation, the present improved holder will be packed for shipment in the condition indicated in Fig. 4 with the handle 4 lying within the casing or blade receiver 1, and when the operator wishes to strop a blade, he simply swings the handle pivotally outwardly which causes one of the edges to engage the detents 7 and spreading the same apart springs the material of plates 3 between the rivet 5 and the outer ends of the blades laterally and retains the parts in such condition until the handle arrives in the position indicated in Fig. 2 when the detents 7 snap into the opening 8, and the parts are thus secured in the extended condition, the holder then being in condition for operation, and it being only necessary to slide the blade 100 into place longitudinally into the casing or blade receiver from the free end thereof. After the stropping operation has been completed the blade is simply slid longitudinally out of the receiver or casing, and the handle 4 swung pivotally to the position indicated in Fig. 4, the detents 7, 7, being thus forced apart and caused to travel across a portion of the handle and allowed to spring together beyond the edge of the handle.

Obviously, various forms of detents may be provided, as for instance, such as is illus-

trated in Fig. 7, in which is seen the usual handle 4, casing or receiver 1, and plates 3, 3, one of the plates being depressed or stamped inwardly as at 7' in position for springing 5 into the aperture 8 in the handle 4.

It is to be noted that the handle 4, when folded into the position indicated in Fig. 4, fits snugly within the casing or receiver 1, and lies therein for the full length of both the 10 handle and receiver, so that the folded structure represents substantially one-half the length of the extended structure, and a neat and compact holder is thus produced.

What I claim is,--

1. In a detachable holder for razor blades, the combination of a blade receiver, a pair of parallel plates connected therewith, a handle pivotally connected to and extending between said plates, and detent means for securing the handle in a relatively rigid condition with respect to the plates when the handle is extended.

2. In a razor blade holder, the combination of a blade receiver terminating at one 25 end in parallel plates, a handle pivotally connected to and extending between said plates and adapted to be swung upon its pivot to and from a position within the receiver, and coöoperating detent means provided respectively on the handle and on one of the plates for retaining the handle in substantially rigid relationship to the receiver when the handle is extended.

3. In a razor blade holder, the combination 35 with a receiver, of a handle pivotally connected thereto and formed with an opening, and a spring detent carried by the receiver and adapted to be sprung into the opening in the handle for effecting a rigid relationship between the handle and the receiver.

4. In a razor blade holder, the combination with a blade receiving clasp, of a handle

pivottally connected thereto, and spring detent means for effecting a rigid relationship 45 between the handle and the clasp.

5. In a razor blade holder, the combination with a receiving clasp, of a pair of parallel plates formed integral therewith, a relatively thin flat handle extending between and 50 pivotally connected to said plates, one of the plates being formed with a laterally extending detent lug adapted to engage one of the side faces of the handle under spring pressure, and the handle being formed with receiving means for the lug for at times effecting a substantially rigid connection between the handle and the clasp.

6. In a razor blade holder, the combination of a blade receiving casing, and a handle pivotally connected thereto and adapted to lie snugly therein, the handle and receiving casing being of substantially the same 60 length and the handle being adapted to lie within and extend from end to end of the 65 casing.

7. In a razor blade holder, the combination of a blade receiving casing, a handle pivotally connected thereto between portions of the receiving casing and adapted to be pivotally 70 swung to and from a position within the casing, and detents carried by portions of said casing, the said handle being formed with an opening adapted at times to receive said detent.

8. In a razor blade holder, the combination with a receiver, of a handle pivotally connected thereto, and engaging means for at times producing a substantially rigid relationship between the handle and receiver. 80

In testimony whereof I affix my signature in presence of two witnesses.

JOSEPH KAUFMAN.
